VEHICLE HEADLIGHT CONTROL

Frank B. Hale, San Francisco, Calif.

Application January 28, 1944, Serial No. 520,081

4 Claims. (Cl. 315—83)

My invention relates to automotive vehicle lighting circuits, and has among its objects and advantages the provision of an improved circuit operating to automatically dim the headlamps on the vehicle as it comes within a prescribed distance from an approaching vehicle with illuminated headlamps, together with a manual control.

The drawing diagrammatically illustrates an electric circuit in accordance with my invention.

In the embodiment of the invention selected for illustration, the drawing illustrates headlamps 10 each provided with a bright light filament 12 and a dim light filament 14. The filaments in each lamp 10 are grounded at 16.

Two relays 18 are provided for the respective lamps 10. Each relay is of the two winding type, one winding in each relay being connected with a wire 20 leading to its respective bright light filament 12. These two windings of the relays are electrically connected by a wire 22. A wire 24 leads from each second winding to the dim light filament 14, and the second windings are electrically connected by a wire 26. A control relay 28 is electrically connected with a wire 30 leading to a contact 32 of a manually operated switch 34. This switch includes a movable contact 36 actuated by a plunger 38 for moving the contact 36 into and out of engagement with the contact 32. The contact 36 is electrically connected with a wire 40 leading to a light sensitive means, such as a photoelectric cell 42, which is mounted on the vehicle in such manner as to be subjected to the light rays from the headlamps of approaching vehicles. A second wire 44 leads from the photoelectric cell 42 to the relay 28.

The wire 40 is electrically connected with a stationary contact 46 of a second manually operated switch 48. The switch 48 includes a movable contact 50 which may be moved into and out of engagement with the contact 46 through the medium of a plunger 52. The wire 50 is connected with the usual battery 54 which is grounded at 56.

Two pilot lamps 58 and 60 are provided. One pilot lamp 58 and one lamp 60 are electrically connected with the wire 40, as by a wire 62. The remaining lamps 58 and 60 are electrically connected with a wire 64 electrically connected with the wire 40, the latter being electrically connected with a movable contact 66 having engagement with a stationary contact 68 when the bright light filaments 12 are energized. The contact 66 is arranged to be attracted by the energized relay 28 to bring the contact into engagement with a

second stationary contact 70 in the switch 72, which includes the contact 68. The contact 70 is electrically connected with the wire 26.

Wires 74 connect the respective lamps 58 with stationary contacts 76 associated with movable contacts 78 grounded at 80. The contacts 78 are arranged to be attracted by the relays 18 to separate from the contacts 76. Each lamp 60 is connected with a wire 82 leading to a movable contact 84. The movable contacts 84 are engageable with stationary contacts 86 grounded at 88. A relay 90 is provided for each contact 84, these relays being electrically connected by a wire 92 electrically connected with the wire 40. Tail lights 94 are respectively electrically connected with the relays 90 and are grounded at 96.

In operation, the switch 48 is closed. Current will then flow through the bright light filaments 12. So long as the photoelectric cell 42 is not subjected to the light rays of approaching vehicles, the switch 72 remains in the condition illustrated, with the contact 66 maintaining engagement with the contact 68. However, when the photoelectric cell is subjected to light rays of approaching vehicles within such distances as are prescribed by law, the relay 28 becomes energized for attracting the contact 66 into engagement with the contact 70 to supply current to the dim light filaments 14. When operating in heavy traffic or in the city, closing of the switch 34 short circuits the photoelectric cell 42 so as to dim the headlamps 10.

The current for the lighting circuit flows through the relays 18. When current is flowing in the circuit, the two relays are energized, thereby breaking the circuits of the indicating lamps 58. Should a filament burn out, the light bulb become loose or a wire should become broken or unloosened and cause opening of the circuit, the lamp 58 in the impaired circuit will become illuminated to indicate which lamp 10 is functioning improperly.

The same is true with respect to the tail light circuits, in that the relays 90 are normally energized and break the circuits through the lamps 60. Impairment of either circuit will cause the lamp 60 in that circuit to illuminate.

Without further elaboration, the foregoing will so fully explain my invention, that others may, by applying current knowledge, readily adapt the same for use under various conditions of service.

I claim:

1. An automotive vehicle illuminating system comprising a circuit having multiple filament

lamps including a bright light filament and a dim light filament a battery in the circuit, a double contact switch for controlling the supply of current to the respective bright light filaments and the dim light filaments a relay of the two winding type in the circuit having a wire from each winding to the bright light filaments and the dim light filaments, respectively, and to the respective contacts of the switch, a relay for actuating said switch, a light sensitive means connected with said latter relay and operating when subjected to light rays from approaching vehicles for energizing said latter relay and actuating said switch to cut off the current supply to said bright light filaments and supply current to the dim light filaments, pilot lamps for the respective filaments, second switches in the circuit for said pilot lamps, and second relays interposed in said circuit for normally maintaining said second switches in open condition.

2. An automotive vehicle illuminating system comprising a circuit having multiple filament lamps including a bright light filament and a dim light filament a battery in the circuit, a switch double contact for controlling the supply of current to the respective bright light filaments and the dim light filaments a relay of the two winding type in the circuit having a wire from each winding to the bright light filaments

and the dim light filaments, respectively, and to the respective contacts of the switch, a relay for actuating said switch, a light sensitive means connected with said latter relay and operating when subjected to light rays from approaching vehicles for energizing said latter relay and actuating said switch to cut off the current supply to said bright light filaments and supply current to the dim light filaments, pilot lamps for the respective filaments, second switches in the circuit for said pilot lamps, second relays interposed in said circuit for normally maintaining said second switches in open condition, tail lamps, third switches interposed in said circuit and electrically connected with said tail lamps, and second pilot lamps respectively connected with said third switches, with said third switches arranged to be maintained in open conditions by said third relays during normal energization of the circuit.

3. The invention described in claim 1 wherein a switch means is provided for short circuiting said light sensitive means for maintaining energization of the dim light filaments.

4. The invention described in claim 2 wherein switch means are provided in said circuit for short circuiting said light sensitive means to maintain continued energization of the dim light filaments.

FRANK B. HALE.
